Charles R. Earle.

UNITED STATES PATENT OFFICE.

JOHN DOYLE, OF HOBOKEN, NEW JERSEY.

RUG-HOLDER.

1,224,615.

Specification of Letters Patent. Patented May 1, 1917.

Application filed October 25, 1916. Serial No. 127,541.

To all whom it may concern:

Be it known that I, JOHN DOYLE, a citizen of the United States, residing at Hoboken, in the county of Hudson and State of New Jersey, have invented an improvement in Rug-Holders, of which the following is a specification.

The invention relates to fasteners for holding a rug in place upon the floor or upon a carpet or other covering laid upon the floor beneath the rug, and the object of the invention is to provide a device which may be easily and inconspicuously engaged with the rug and secured to the floor beneath the latter. A further object is to provide means for the insertion of a suitable implement beneath the device whereby it may be easily and quickly drawn from the floor and without appreciable damage to the floor surface.

The invention consists in certain novel features and details of construction and arrangement by which the above objects are attained, to be hereinafter described and claimed.

The accompanying drawings form a part of this specification and show approved forms of the invention.

Figure 1 is a perspective view of a preferred form of the device.

Fig. 2 is a plan view on a small scale showing a portion of a rug and the relation of the holders thereto.

Fig. 3 is a plan or top view of one of the holders alone, on a larger scale.

Fig. 4 is a corresponding view of the under face.

Figure 5 is an edge view. The dotted lines show the relative positions of the holder, rug, and floor when in service.

Fig. 6 is a section taken on the line 6-6 in Fig. 4.

Fig. 7 is a plan or top view of a modified form of the device.

Fig. 8 is an edge view corresponding to Fig. 7.

Fig. 9 is an enlarged detail in edge view. Similar letters of reference indicate like parts in all the figures.

Referring to Figs. 1 to 6 inclusive, A is a plate or triangular disk preferably of sheet steel having at each angle a prong or spur B formed integral with the plate and bent downwardly to project at a right angle to the under face of the plate.

Across the upper face of the plate lies a

wire C secured in place by solder or otherwise, having its outer ends projecting upwardly as pins D D.

The plates are attached to the rug M, 60 preferably one at each corner, by passing the points of the pins D D through the rug from below and folding the pins downwardly parallel with each other as indicated by the dotted lines in Fig. 5, to engage the rug between them and the plate A. The pins D D are pressed firmly down and lie concealed in the pile of the rug. The rug is then placed in the desired position upon the floor and the spurs B B on each of the 70 plates driven into the floor by pressure of the foot upon the upper face of the rug, either directly into the floor or through a carpet or other floor covering, not shown. The pressure thus applied also embeds the 75 pins D D in the upper face of the rug and aids in concealing them.

The operation of bending the spurs B B downwardly at a right angle to the under face of the plate causes the root of each to 80 form a short curve at b which prevents the spur from entering its full length into the floor and thus holds the plate with its lower face out of contact with the floor surface 85 and provides a slight opening or space 90 adapted to permit the entrance of an implement by which upward pressure may be exerted upon the plate and the spurs thus withdrawn to release the rug, see Fig. 9. This slight elevation of the plate avoids 95 marring the floor excepting the small punctures made by the spurs.

Figs. 7 and 8 show a form in which a single spur B¹ is employed, centrally located on the under face of the plate A¹ and consisting preferably of a tack thrust through a hole in the plate and its head B² soldered upon the upper face of the plate. The pins D¹ D¹ are similar to those above described but the wire C¹ of which they are formed is in two pieces separated by the tack-head B². This form of the holder is attached to the rug and engaged with the floor in a manner similar to that described, and the desired elevation of the plate above the floor to permit the insertion of a lifting tool is effected by bending the angles of the plate slightly downward as at A² to produce short legs or supports.

The shape of the plates may be varied as desired, as may the length of the spurs and their number and location.

I claim:—

The rug holder described comprising a plate having a downwardly extended spur on its under face adapted to engage a floor, 5 upwardly projecting pliable wire pins on its upper face adapted to penetrate a rug and fold downwardly thereon, said plate being formed at its edge with means to hold said plate with its lower face out of contact with

the floor surface to permit of the entrance 10 of a lifting implement beneath said plate.

In testimony that I claim the invention above set forth I affix my signature, in presence of two witnesses.

JOHN DOYLE.

Witnesses:
